UNITED STATES PATENT OFFICE.

JAMES HEWITT BALDWIN, OF ENGLEWOOD, NEW JERSEY, ASSIGNEE TO DULLES-BALDWIN ELECTRIC DRILL COMPANY, OF NEW YORK, N. Y., A CORPORATION OF NEW YORK.

IMPACT MECHANISM.

1,159,462.

Specification of Letters Patent.

Patented Nov. 9, 1915.

Application filed March 19, 1913. Serial No. 755,294.

To all whom it may concern:

Be it known that I, JAMES H. BALDWIN, a citizen of the United States, residing at Englewood, in the county of Bergen and State of New Jersey, have invented certain new and useful Improvements in Impact Mechanism, of which the following is a full, clear, and exact description.

The invention which forms the subject matter of this application relates to an improvement in an impact mechanism wherein the power is communicated to the bit, hammer or other tool through the instrumentality of the air in the cylinder or casing.

In devices of this character it not infrequently happens that the machine may not be properly adjusted to deliver its blow so that during the operation the air partially escapes from the cylinder through the head thereof and, if no provision be made to take up the force of the blow, the piston will strike forcibly against the said head, resulting in damage and injury.

It is the object of this invention to overcome this defect.

Referring to the drawing wherein I show the preferred embodiment of the invention, Figure 1 shows a longitudinal section of an impact mechanism with my improvements embodied therein. Fig. 2 shows a sectional view of the cylinder taken on line 2-2 of Fig. 1, and looking in the direction of the arrows.

In detail, the character 10 designates the outer casing of an impact mechanism, for example, a rock drill, having a cylinder 11 reciprocable therein.

To the head 12 of the cylinder is connected an arm or pitman 13, the latter connected to a motor or other suitable power means 14 through the intermediate crank shaft 15, and gears 16 and 17 connected to said crank-shaft and motor respectively.

Within the cylinder 11 is a piston 18 provided with a stem 19 which passes through the lower head 20. This piston is freely movable in the cylinder, save for the resistance offered by the air when the piston moves toward either end thereof. The cylinder itself has free reciprocating motion in the chamber 21, said motion being imparted thereto by the power means 14, above referred to. The lower end of the chamber 21 is defined by the upper end of the mem-

ber 22 which telescopes with the casing 10. The piston-stem 19 passes through a pawl-disk 23 located in the upper portion of the member 22. The grooves 24 (only one shown) coöperate with this disk 23 to give the piston a slight rotation each time that the same is moved upward, the said disk being held stationary on the upward movement by means of pawls (not shown) projecting therefrom and engaging with a flanged disk 25 on the member 22. The stem 19 passes centrally through the member 22 and is connected at its lower end to a chuck 26 which in turn makes suitable connection with a bit, hammer or other tool (not shown). The piston stem is provided with an enlargement at 27 which reciprocates freely within the chamber 28 of the member 22. The latter is provided with an inwardly projecting flange 29 and is secured to the casing 10 by means of a resilient connection which comprises the bolts 30 passing through ears 31 on the member 22 and through corresponding ears 32 on the casing 10. One of the ends of the bolts is provided with heads 33 while the other is provided with nuts 34. Located between the nuts 34 and the ears 32 are resilient or cushioning means 35.

Upon the cylinder 11 I mount a sleeve 36 provided with grooves 37 connecting the ports 38 in the said cylinder. A handle 39 is employed to operate the sleeve 36. The handle straddles the projection produced by one of the passages 37 and by means of the sleeve and operating handle the flow of air through the passages can be regulated as desired, or stopped entirely. When cut off entirely perforations 40 in the cylinder may be made to register with corresponding perforations (not shown) in the sleeve. The sleeve 36 is held against longitudinal movement by means of the screw-threaded sleeve 41, which forces the former against a shoulder at the opposite end of the cylinder. This mechanism just described I do not claim herein as the same forms the subject matter of a separate application.

The operation of the device is as follows: In the position shown in Fig. 1, the cylinder 11 is descending and the air therein above the piston, since the latter is above the air port 38, is being compressed and the power transmitted by the motor through the crank-shaft is being imparted to the

piston through said air in the upper end thereof. The downward movement is continued until the lower end of the cylinder 11 is at the lower end of the chamber 21 when 5 the same will begin to rise being positively operated by the crank shaft 15. The piston however will continue its downward movement owing to its momentum particularly so if the drill bit is out of contact with 10 the object being drilled. This momentum may be so great as to force all the air out of the cylinder below the piston owing to the fact that it is impossible, on account of connections, to make the lower head air-tight. 15 In this case, unless some provision be made, the piston would strike forcibly against the lower head resulting in damage or injury, and whether or not any immediate injury or damage be done the constant pounding of 20 the same in this manner will soon result in permanent injury to the impact mechanism as a whole. But with my improvements this cannot take place, since the enlargement 27 on the piston stem 19 will contact with the 25 inwardly projecting flange 29 before the piston has had time to strike against the head 23. The blow will be communicated from the member 22 to springs 35 and hence cushioned by the latter.

30 It is obvious that changes can be made in point of detail and it is to be understood that the specific embodiment shown herein is simply the preferred form and that the principle can be embodied into other form without departing from the spirit and scope of 35 this invention.

What I claim is:

1. In an impact mechanism having a body portion, a power driven reciprocatory cylinder, a piston movable axially in the cylinder and operatively connected therewith by the elastic body of air inclosed between the piston and the ends of said cylinder, a stem connected to said piston, in combination 40 with a cushioning means on said body portion and engaged by said stem to prevent the 45

piston from striking the lower end of the cylinder.

2. In an impact mechanism, a power driven reciprocatory cylinder, a piston movable axially in the cylinder and operatively connected therewith by the elastic body of air inclosed between the piston and the ends of said cylinder, a stem connected to said piston, and normally inoperative means independent of the power driven cylinder and engageable by said stem upon an extreme movement of the piston to cushion the blow imparted to the said piston and stem. 50

3. In an impact mechanism having an outer casing, a power driven reciprocatory cylinder movable within said casing, a piston movable axially in the cylinder and operatively connected therewith by the elastic body of air inclosed therein, a stem connected to said piston and passing through one end of the cylinder, a member resiliently connected to the casing, and means on said stem to engage the said member to prevent the piston from making contact with said 65 cylinder end. 70

4. In a device of the class described, a casing, a cylinder movable within said casing, a piston movable axially within said cylinder and operatively connected therewith by the elastic body of air inclosed therein, in combination with a cushioning mechanism comprising a member telescoping with the aforesaid casing and having a chamber 75 therein through which the piston stem 80 passes, resilient means normally holding the member in one extreme position, and means on said piston stem adapted to engage with said member to cushion the extreme forward stroke of the piston and stem. 85

In testimony whereof I affix my signature in the presence of two subscribing witnesses.

JAMES HEWITT BALDWIN.
